[57] CLAIM

The ornamental design for a cowling, as shown and described.

DESCRIPTION

FIG. 1 is an elevated rear perspective view of a cowling showing our new design, the broken line showing of the vehicle and tool being for illustrative purposes only, and forms no part of the claimed design;

FIG. 2 is an enlarged top view of the cowling design of FIG. 1;

FIG. 3 is an enlarged rear view of the cowling design of FIG. 1;

FIG. 4 is an enlarged right side view of the cowling design of FIG. 1; and,

FIG. 5 is an enlarged left side view of the cowling design of FIG. 1.
